UNITED STATES PATENT OFFICE.

CARL STEINBERG, OF NEW YORK, N. Y.

STRAW HAT.

Application filed June 22, 1928. Serial No. 287,391.

My present invention relates generally to straw hats and more particularly to the type of straw hat which has a relatively rigid crown portion and a relatively rigid brim portion, and an intermediate section connecting said portions so as to provide a flexible, intermediate portion. Such a type is shown in my Patent No. 1,643,138.

Straw hats of the character disclosed herein and in connection with which my invention is to be primarily employed, consist of a crown and a brim, each made up of straw braid arranged spirally with the adjacent spirals secured together in any preferred or desired manner to cause them to maintain their predetermined shape. Body and rigidity are given to the braid assembly forming the crown of the brim by means of any preferred filling, sizing or adhesive material.

The object of the present invention is to provide a straw hat having the flexible part interconnecting the crown and the brim so constructed as not only to simplify and cheapen the process of manufacture but to increase the flexibility of the intermediate portion and improve the wearing characteristics of the hat as a whole.

Other objects of my invention will either clearly appear or be pointed out hereinafter.

In the embodiment of my invention illustrated in the drawings and described in the specification, the intermediate portion of the hat interconnecting the crown and the brim is in the form of spirally wound braid laid edge to edge. The adjacent edges of the spirals forming the intermediate portion are secured together, edge to edge, by means of stitches connecting the adjacent spirals, so as to provide at the edges of contact between the adjacent braid a connection which permits of increased flexibility.

For the attainment of these objects and such other objects as may hereinafter appear or be pointed out, I have illustrated in the drawings one embodiment of my invention, wherein—

Fig. 1 is a perspective view of a straw hat embodying my invention, with a portion of the band broken away so as to expose the underlying construction.

Fig. 2 is a slightly exploded section taken diagrammatically vertically through the straw hat of Fig. 1.

Fig. 3 is a section similar to Fig. 2 showing the parts connected.

Fig. 4 is a fragmentary perspective view

showing a portion of the intermediate connecting section; and

Fig. 5 is a fragmentary side elevational view of Fig. 1, taken on the level with the 60 brim.

Referring to Fig. 1 of the drawings, it will be seen that the straw hat comprises a crown portion 10, a brim portion 11, and the connecting intermediate, flexible section 12 connected to the crown portion along the line *a* and to the brim portion along the line *b*. The crown and the brim portions are formed in any preferred or desired manner, and of any character of braid, these portions being illustrated in the drawings as made up in the conventional way of relatively wide braid, of comparatively loose weave, having one serrated edge 16 and a smooth edge 17.

In forming these portions from this type 75 of braid, it is customary to start at the center of the crown, indicated at 19, and cause the braid to curl spirally first outwardly and then downwardly toward the band portion, so as to have the adjacent edges of the adjacent curls 80 superposed one upon the other, with the smooth edge of each convolution under the serrated edge of the preceding convolution. These curls are then secured together in any preferred or desired manner, as by stitching, 85 so as to form the crown portion of the hat. The brim portion 11 is formed in the same manner as is the crown portion, except that it is illustrated in the drawings as made up of two separate layers 11' and 11'' connected together and to the intermediate portion in a 90 manner that will shortly be described.

It is usual where the curls or convolutions forming the brim or the crown portions are secured together by stitches, to employ a concealed stitching machine so that the stitching 95 will not be apparent to the observer.

The intermediate connecting section 12 is illustrated in Fig. 3, and is made up of two portions 12' and 12'' associated together, and 100 with the crown and brim portions, in a manner which will also be shortly pointed out, it being sufficient for the moment to state that these portions 12' and 12'' are formed in the same manner, and a description of the formation of one will suffice for both.

The braid employed in forming the intermediate section 12 is preferably smooth on both sides and has no teeth and may be of any desired or preferred width. To form the intermediate section this character of braid is spiralled first downwardly in a vertical plane

and then in a horizontal plane, with the adjacent spirals 12³ all arranged in a common plane and without overlap, so as to bring the adjacent edges 12⁴ of the adjacent spirals into edge-to-edge engagement. The adjacent spirals are then secured in this position by a stitch which passes from one spiral to the adjacent spiral across the joint between the two, and in the embodiment herein disclosed I show the employment of the zig-zag stitch 20 for this purpose.

The assembling of the various sections to form the straw hat comprises the following steps: The crown and brim portions 10 and 11 are first made complete and may be stiffened or loaded before assembling. The upper part 12' of the intermediate section is first secured to the brim by a zig-zag stitch, as shown in Fig. 5 of the drawing, with the lower edge of the crown portion, illustrated in this embodiment, as superimposed above the upper edge of the outer section 12' of the intermediate part of the hat. It will be understood, of course, that both sections 12' and 12'' are made with portions one in a horizontal plane and another in a vertical plane so as to have them conform to and form continuations of the crown and brim portions of the hat, respectively.

30 The horizontal portion of this part 12' is then secured to the upper member or layer 11' of the brim 11 by zig-zag stitches, with the edge of the part 12' superimposed above the inner edge portion of the brim member 11'. The lower member 12'' of the intermediate section 12 is attached to the lower brim member 11'' by zig-zag stitches, with the position of the superimposed edges of the two reversed from that shown in connection with the upper brim member. The parts are then assembled by sewing the free upper end of the lower flexible portion 12'' to the vertical portion of the member 12' by any preferred or desired character of stitching. This will 45 complete the assembly of the hat.

I have found that by forming the intermediate section of the braid spirally wound and secured together in the manner set forth in this specification, I have attained the following results and advantages. By employing an edge-to-edge contact I have eliminated the tendency of the extending superimposed or overlapping portions of the adjacent spi-

55 rals to curl upwardly at their free edges and to avoid which it has been customary hitherto to load these edges with glue. By binding these edges to each other in the manner set forth, this curling tendency is eliminated and therefore also the necessity for loading them down with glue or similar substances.

60 In the use with an edge-to-edge contact the stitches overlying this contact and passing from one edge to the other, provide a joint, the flexibility of which is materially increased without adversely affecting the ruggedness or the wearing characteristics of the structure. Furthermore, the use of this zig-zag stitching in the manner set forth permits of this character of stitching forming part of the hat design so as to add considerably to the 70 effectiveness of the appearance of the hat.

Having thus described my invention and illustrated its use, what I claim as new and desire to secure by Letters Patent is:—

75 1. A straw hat comprising a relatively rigid crown part, a relatively rigid brim part, and a flexible section intermediate of and connecting the two, said section comprising a braid wound so as to cause the adjacent convolutions to present their adjacent edges 80 with an edge to edge contact in a common plane, and means for securing the adjacent edges in such contact whereby the flexibility of said intermediate section is increased.

85 2. A straw hat comprising a relatively rigid crown part and a relatively rigid brim part made up of two superposed sections, said crown part and said brim sections being formed of straw braid arranged in spiral overlapping relation, and a flexible part comprising two superposed sections each comprising braid positioned edge to edge and secured together edge to edge with a vertical portion and a horizontal portion, the upper 90 of said intermediate sections being secured to the crown part at one end and upon the upper of the brim sections at its other end, and the lower of said intermediate sections being secured at one end to the vertical portion of 95 said first-mentioned intermediate section and at its other end to the lower of said brim sections.

100 In witness whereof I have hereunto signed my name this 14 day of June, 1928.

CARL STEINBERG.
